UNITED STATES PATENT OFFICE.

EDNA SORTELLE AND VERNON C. PORTER, OF NEW YORK, N. Y.

TELEPHONE MOUTHPIECE.

Application filed February 2, 1926. Serial No. 85,453.

Our invention relates to telephone mouth pieces, and particularly to a mouth piece adapted for use upon telephones, and in other like connections, to gather in the sound waves as a person talks into the mouth piece and to shut out outside noise in intervals in the conversation.

An object of this invention is to provide a mouth piece which will be normally set for use, and which can be manually adjusted to close out outside noise.

A further object resides in so constructing the parts that the mouth piece is automatically restored to the open or receiving position when released.

Still another object is to provide a mouth piece which is of substantially standard form and design and which can be applied to and used upon telephone and other mechanisms without alteration of the structure thereof.

With the above and other objects in view which will be apparent to those skilled in the art, the invention includes certain novel features of construction and combination of parts which will hereinafter be described and pointed out in the drawings.

Figure 1 is a view in section through a mouth piece constructed in accordance with our invention.

Figure 2 is a view in end elevation looking into the mouth piece.

Figure 3 is a transverse sectional view substantially on the line 3—3 of Figure 1.

Figure 4 is a view similar to Figure 1, showing a modified construction of the mouth piece.

Figure 5 is a sectional view substantially on line 5—5 of Figure 3.

Our improved mouth piece can be made of vulcanized rubber, glass, synthetic compositions such as a phenolic condensation product, and in fact of any suitable material. A supporting member 1 is externally screw threaded at 2 adjacent one end, to fit the threaded portion provided on the telephone or other instrument for reception of the mouth piece and at its remaining end, this supporting member has the cover 3 provided with a plurality of perforations 4. These perforations are preferably slightly spaced so that solid spaces are provided therebetween, of a width slightly greater than the diameter of the perforations, and it is also preferable that the perforations or openings be grouped or formed substantially concentrically around the central bear-

ing opening 5. The mouthpiece 6 is of substantially the usual mouth piece form and has the end wall 7 thereof provided with perforations 8 substantially corresponding with the size and location of the perforations 3. This inner wall 7 is provided with a central bearing opening 9 which registers with opening 5.

The mouth piece 6 has a groove 10 formed on its inner end concentrically around the bearing opening 9 and the supporting member 1 is provided with a rib 11 to fit within this groove and establish a substantially tight joint between the supporting member 1 and the mouth piece. A rivet or bolt 12 is fitted through the bearing openings 5 and 9, and a coil spring 13 is preferably mounted on this rivet or bolt with one end bearing against the inner head or nut of the rivet or bolt and the remaining end bearing against the wall 3.

With the parts constructed and mounted in the manner set forth, the mouth piece can be adjusted with respect to the supporting member to bring the openings 4 and 8 into registry so that the mouth piece will be open in substantially the same manner as an ordinary telephone mouth piece, or the mouthpiece 6 can be slightly twisted or turned to bring the solid intermediate portions of the one member over the adjacent ends of the openings or perforations of the other member. To insure that the mouth piece member normally will be held in a position with the perforations or openings thereof in registry with the perforations or openings of the supporting member we provide one or more springs 14. These coil springs are mounted in the curved grooves 15 and 16 in the mouth piece and support, which grooves are substantially semi-circular in cross section to thus provide for reception of substantially one half of the coil spring by the groove of each member. The grooves 15 and 16 have their ends squared and the grooves are preferably so formed that the squared ends are in alignment when the openings or perforations 4 and 8 are in registry.

In this way, the springs 14 will serve to normally resiliently urge the movable mouth piece member 6 to a position in which the perforations register and abutment of the ends of the spring 14 against the ends of the grooves 15 and 16 will stop movement at such a point that accurate registry of the perforations is insured.

Under some circumstances and conditions it may be found advisable to provide positive stop means to limit turning movement of the mouthpiece 6 to the closed position and this can be accomplished by providing the curved slot 17 in one of the members and mounting a pin 18 on the remaining member to work within the slot. Under some conditions it may be found practicable to make the spring 14 of such length that when compressed to its fullest extent it will effectively stop further rotative movement of the mouthpiece 6 at such a point that the openings or perforations are effectively closed.

As illustrated in Figure 4, the mouthpiece and the supporting members are each provided with the registering grooves 18 and 19 and a gasket or washer 20 is inserted within this groove. With this construction the main bearing between the two members will be upon the ring washer or gasket, and frictional engagement between the wall or ends 3 and 7 will be relieved. However, with some materials, and in some connections, it may be found advisable or desirable to insert a thin layer of felt or other suitable material, as indicated at 21, to prevent rasping or grating sounds as the mouthpiece is turned. In most instances, any objectionable frictional contact and consequent noise can be reduced by coating lightly with graphite or other lubricant between the two ends.

While we have herein shown and described only certain specific embodiments of our invention and have suggested only certain possible modifications, it will be appreciated that changes and variations can be made in the form, construction and arrangement of the parts without departing from the spirit and scope of our invention.

We claim:

1. A telephone mouth piece comprising a supporting member having perforations therethrough, a mouth piece revolubly mounted on the supporting member and provided with perforations to be brought into and out of registry with the perforations of the supporting member as the mouth piece is turned, and a spring normally resiliently urging the mouth piece to a position in which the perforations register.

2. A telephone mouth piece comprising a supporting member having perforations therethrough, a mouth piece revolubly mounted on said supporting member and

provided with registering perforations, said supporting member and mouth piece having registering grooves therein with abutments at the ends of the grooves, and a spring 60 mounted in said grooves to normally resiliently urge the mouthpiece to a position with the perforations thereof registering with the perforations of the supporting member.

3. A telephone mouth piece comprising a supporting member having perforations therethrough, a mouth piece having a closed end provided with perforations, a pin revolubly mounting the mouth piece upon the supporting member with the perforations 70 of the closed end adjacent the perforations of the supporting member, a spring resiliently drawing the two members together, and a spring normally resiliently urging the mouth piece to a position with the perforations in registry. 75

4. A telephone mouth piece comprising a supporting member having perforations therethrough, a mouth piece having a closed end provided with perforations, a pin revolubly mounting the mouth piece upon the supporting member with the perforations of the closed end adjacent the perforations of the supporting member, a spring resiliently drawing the two members together, a spring 85 normally resiliently urging the mouth piece to a position with the perforations in registry, and means to stop revoluble movement of the mouth piece with the perforations thereof out of registry with the perforations 90 of the supporting member.

5. A telephone mouth piece comprising a supporting member having perforations therethrough, a mouth piece having a closed end provided with perforations, a pin revolubly mounting the mouth piece upon the supporting member with the perforations of the closed end adjacent the perforations of the supporting member, a spring resiliently drawing the two members together, a spring 100 normally resiliently urging the mouth piece to a position with the perforations in registry, means to stop revoluble movement of the mouth piece with the perforations thereof out of registry with the perforations 105 of the supporting member and a packing between the two members.

In testimony whereof we affix our signatures.

EDNA SORTELLE.
VERNON C. PORTER.
